LIGHTING FIXTURE

William E. Laidley, Chicago, Ill., assignor to
Clarence L. Steber, Chicago, Ill.

Application January 8, 1940, Serial No. 312,885

2 Claims. (Cl. 240—81)

This invention relates to electrical fixtures, and particularly to electrical fixtures embodying a fluorescent lamp.

An important object of the invention is to provide a lighting fixture, employing a vertically disposed column of light, such as a fluorescent lamp, and the provision of new and improved means for shading and reflecting the light generated by the fluorescent lamp, so as to provide the proper amount of light, but at the same time preventing and overcoming glare.

Another important object of the invention is the provision of a lighting fixture having a vertical column of light, there being a plurality of vertically spaced, cylindrically arranged shades to prevent the light rays generated by the lamp from being cast directly into the eyes of the user, but to reflect or diffuse the light properly so as to overcome glare.

A further object of the invention is the provision of a vertically disposed column of light, having a reflector arranged at one side thereof to deflect or reflect the light forwardly to the working space, as well as reflecting or deflecting the light downwardly, the same being accomplished by a vertically disposed reflector arranged at one side of the lamp and a plurality of conical shaped, concentrically arranged spaced reflectors or shades.

A still further object of the invention is the provision of a plurality of concentrically disposed, vertically arranged shades or reflectors, cooperating with a vertically disposed column of light, the reflectors having their sides converging, the angle of inclination of the vertical sides varying from one end of the lighting fixture to the other, there also being means provided to effect adjustment of the conical shaped shades.

A still further object of the invention is the provision of a vertically disposed reflector element arranged adjacent a vertical column of light, the reflector having its inner or reflecting surface provided with concave surfaces so that the light generated by the lamp will be properly reflected or deflected outwardly about the lamp and will not be reflected back into the light source.

Another object of the invention is to provide a fixture having a source of light, such as a fluorescent lamp, wherein the light source is close to the inner surface of the glass tube, whereby the beams coming to a viewer are transmitted through the glass at a wide angle with respect to the perpendicular, or normal to the surface at the point of penetration, and the

width of the surface is along the length of the tube, whereby the light is considerably polarized in the direction of the length of the tube.

Still another object of the invention is to provide a light fixture employing a fluorescent tube, the fluorescent tube being arranged vertically so as to overcome glare, as the light source, being set perpendicular to a reflecting surface, such as a horizontal working plane, will be vertically polarized when it strikes the horizontal plane.

Still another object of the invention is the provision of a reflector or diffusing unit to control the distribution of light from a tubular, gaseous lamp, such as a fluorescent lamp, that will partially or totally obscure the lamp from view from certain directions, and limit radiation at certain angles, and direct and control the light in other directions by utilizing direct and reflected, and, if desired, diffused radiation from the tube by means of a series of disks or conics, or a spiral of the same order, placed concentric, or, more properly, symmetrical to the longitudinal axis of the lamp tube, and more particularly, but not essentially, to arrange these above described reflecting or diffusing surfaces to use the lamp with its longitudinal axis in a vertical position with respect to the working plane and to thereby obtain more satisfactory utilization and distribution of light.

Numerous other objects and advantages will be apparent throughout the progress of the following specification.

The accompanying drawings illustrate selected embodiments of the invention, and the views therein are as follows:

Fig. 1 is a detail elevational view of a lighting fixture embodying the invention;

Fig. 2 is a detail elevational view of a modified form of lighting fixture embodying the invention, and provided with a vertically disposed reflector and means for effecting adjustment of the various shades;

Fig. 3 is a diagrammatic or schematic view showing one form of reflector which will direct or diffuse the light rays directly into the source of light;

Fig. 4 is a similar diagrammatic view along the line 4—4 of Fig. 2, but showing reflector means for catching and reflecting the light throughout various angles;

Fig. 5 is an elevational view of a desk lamp embodying the invention, having a plurality of spiral, conic shades concentrically arranged about a vertically disposed fluorescent lamp,

there being means provided for adjusting the lamp fixture with respect to its base;

Fig. 6 is a view similar to Fig. 5, showing a one-piece spiral reflector about a vertically disposed fluorescent tube, the inclination of the shade becoming flatter as they progress upwardly;

Fig. 7 is a sectional view taken on the line 4—4 of Fig. 2.

Fig. 8 is a sectional view taken on the line 8—8 of Fig. 6.

Referring to Fig. 1 of the drawings, 1 designates a base to which a cable 2, carrying electrical conductors, is operatively connected. The base 1 is provided with a swivel or universal joint connection 3, with a member 4 carried by a vertical column or support 5, whereby the vertical column 5 may be swung throughout various vertical angles with respect to the base 1. The electrical connectors in the cable or conductor 2 make electrical connection with a vertically disposed source of light 6, which is preferably a tubular lamp, known as a fluorescent lamp.

A plurality of distorted cone shaped shades 7 are concentrically arranged about the lamp 6, and these cone members 7 have their side walls inclining and converging upwardly, the angle of the lowermost member 7 being relatively flat, as indicated at 8, while the uppermost member 7 has a relatively straight or more vertical angular wall, as indicated at 9. The intermediate members 7 have the inclination at the side walls increasing to the vertical as they progress upwardly, whereby the sharpest angle is at the top, while the flattest angle is at the bottom. A cap 10 is removably connected to the standard 5, being detachably connected to the standard 5 by means of a thumb nut or other fastening element 11. The conical shaped members 7 may be supported in any desired manner and are shown as fixed to the standard 5 by any convenient means, such as by soldering, or otherwise, as indicated at 12, Fig. 1.

Fig. 2 also shows a plurality of distorted conical shaped shades 7, but the walls 13 thereof flatten as they progress upwardly, whereby the steepest angle is at the bottom, as indicated at 14, while the flattest angle is at the top, as indicated at 15. The angle of the walls intermediate the members 14 and 15 incline more to the horizontal as they progress upwardly. The lowermost shade 7, indicated by the numeral 16, Fig. 2, is relatively flat and assumes a shape similar to that disclosed as at 15.

In the embodiment shown in Fig. 2, the conical shaped shades 7 are hingedly connected to the standard 5 as at 12a, Fig. 7, and an adjusting member 17 is provided for tilting the shades 7 on their pivots, whereby the forward projecting edges may be tilted. The tilting means 17 may comprise a rod or any other element, but is shown herein specifically as comprising a chain 18. Connected to the edges of the members 7, as indicated at 19, Fig. 2, the chain extends upwardly through the cap 10 and terminates into a control or operating member 20. When the lever or manipulating element is pulled upwardly, the forward peripheral edges of the member 7 will be raised upwardly. When the member 20 is released, the member 17 will drop to normal position by gravity, although the chain 18 may extend beyond the bottom member, as indicated at 21, to permit all the members 7 to be pulled downwardly in the desired position. The member 20 cooperates with a

latching or holding device to cause the devices to remain in adjusted position.

The reflector 22 is semi-cylindrical in shape and extends vertically from the base 1 up to the cap 10, as clearly shown in Fig. 2. If the reflector 22 were made semi-cylindrical, as shown in Fig. 3, with the inner concave surface 23 thereof being in the form of a regular curve, the light expended or radiated from the tube 6 would tend to be reflected back into the tube, and therefore very little reflection or radiation would be reflected back to the working surface. It is desirable, therefore, that the reflector 22 be provided with an inner multiple curved section 24, Fig. 4. This irregular curved portion 24 may comprise a pair of concave surfaces 25, terminating or meeting at the apex indicated at 26, Fig. 4. This latter arrangement causes the light radiating from the light source thus to be deflected throughout various angles, as indicated by the directional arrows 27, Fig. 4.

The vertical reflector 22 is designed for a cylindrical column of light, such as a fluorescent lamp. It has a curvature so that rays of light propagated from any point on the cylindrical source, upon striking the reflector, will be reflected at such an angle that it will not be returned in a direction to strike any point on the surface of the lamp globe, thereby overcoming the interference and loss of light energy that would be inherent in a reflector not designed in this manner. The curvature need not be in the specific form indicated, but should be of a design capable of reflecting the light at an angle and not return in a direction to strike the lamp globe. The curve or inner reflecting surface 24 may be a spiral, ellipse or compound curve with centers or curvatures set in a predetermined relationship.

In Figs. 5 and 6, there is disclosed a similar type of lighting fixture, each having a base 1, as previously described. The base 1 may be rigidly connected to the standard 5, as shown in Fig. 6, or it may include the swivel connection 3—4, Fig. 5. The vertical fluorescent tube 6 is surrounded by a continuous spiral 30, Fig. 5, providing a spiral deflector for the tube 6 and deflecting the light downwardly. In Fig. 5, the angle of inclination of the spiral is relatively flat, as indicated at 31, while the angle at the top is relatively straight, as indicated at 32. The parts of the spiral shade intermediate the parts 31 and 32 gradually become more vertical progressively from the bottom to the top. In Fig. 5, the standard 5 is shown positioned exteriorly of the reflector 22, while Fig. 6 shows the reflector 22 encasing the standard 5. In Fig. 6, the spiral 30 flattens at the top, as indicated at 34, and becomes steeper toward the bottom, as indicated at 35. Therefore, the vertical angle of inclination of the defining side walls of the spiral become flatter progressively from the bottom toward the top.

The conical and spiral reflectors may have a similar curvature indented on what would be called the rear portion, particularly when they are used in the manner indicated without a rear vertical reflector, and may have a large portion of their surface toward the vertical reflector cut away to permit the vertical reflector to redirect all the rays propagated in its direction.

The lamp 6, when placed in a vertical position, will cause less glare from the working plane, within the vision of the viewer, than when placed in a horizontal position. Thus if the light 6 is ar-

ranged in a horizontal position, and a reflector directs the light rays to a plane surface, which may be a desk top, the reflection on the desk top will be an elongated rectangular strip of bright light which, when hitting the surface, will rebound back in the form of a glare. The entire longitudinal or horizontal surface of the light member 6 will rebound back at an angle in the form of glare.

Where the light source 6 is in the form of a vertical column, however, there may be an image or reflection but the length of the image will be considerably shorter than the height of the vertical column 6, and no glare will occur, as the light will be polarized. At most, only a short, cloudy portion will be apparent. The result is that the light radiating from the vertical tube 6 will rebound back in the form of seeing light.

The radiation of the disks or conics 7, or spirals 30, need not be a complete 360° angle, nor need they be symmetrical for their complete 360° of angle. They may include distortions of the curvatures or surfaces of the disks, or conics, or spirals, or they may be used in combination with surfaces such as a vertical reflector parallel with the longitudinal axis of the tube, either of a flat or curved section, to intercept a portion or all of the illumination radiated in certain directions about the circumference of the tube and redirect this radiation into certain other directions where it is more desired.

The present invention is applicable to and intended, among other uses, for desk or work table lighting where it is desirable to shield the direct light from the eyes of the worker and place the light on the working plane either in all directions about the lamp, or to direct the light in some preferred limited direction less than 360° circumference about the lamp, say 180° more or less. The present invention is also applicable to wall or column mounting to place the light in the working plane in all, or in certain portions of the horizontal circumference about the lamp and to partially or totally shield the lamp from certain directions; also to mount the lamp perpendicular to the wall and direct the radiation onto the wall or in any other direction. In the case of ceiling mounting, the lamp is placed in a vertical position with the shades or reflector directing the light rays against the ceiling.

The invention provides more satisfactory illumination than will be obtained over other means, such as horizontal mounting of the tube with a reflector of the ordinary type, for the projected depth of illumination source is widened and the width narrowed in comparison with the ordinary type of unit, giving more wide angle

distribution from an unequal spherical distribution characteristic of the tube and diminishing the amount of objectionable reflected glare, and diminishing the width of angle from which it is directed toward the worker.

When a horizontal circumference or angle is mentioned, it is to be considered that the main direction of propagation may be in a direction by some angle below a horizontal working plane, such as a desk, or in a plane at some angle above the circumference, such as a ceiling, etc. In most applications, the radiation will be mostly applied to a working plane perpendicular to the longitudinal axis of the tube and removed in either direction from a central perpendicular plane, along the direction of the longitudinal axis.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A lighting fixture comprising a base, a vertically disposed elongated cylindrical lighting element mounted on said base, a plurality of concentrically arranged, vertically spaced shades about said light and supported from said base, each shade having upwardly inclined converging side walls, the angle of inclination of said side walls progressively increasing in one direction, and a unitary curved reflector arranged on said base to extend vertically adjacent said tubular element and in partial surrounding relation with respect thereto, said vertical reflector having a plurality of separate reflecting surfaces arranged to reflect light in directions away from said lighting element.

2. A lighting fixture comprising a base, a tubular fluorescent lamp arranged on said base in a vertical position, a support on the base adjacent the lamp, a plurality of vertically spaced concentric shades forwardly of the support and arranged around said tubular lamp, each shade having inclined converging side walls, the angle of inclination of said side walls progressively increasing in one direction, means pivotally connecting the shades to the support, means operatively connected to said shades to adjust said shades on their pivots, and a vertical unitary concave reflector mounted on said base behind the lamp, said reflector having a reflecting surface made up of a plurality of converging concave surfaces.

WILLIAM E. LAIDLEY.
